UNITED STATES PATENT OFFICE.

ESTELLA S. ORR, OF CLEVELAND, OHIO.

BUST-FORM.

1,179,137.

Specification of Letters Patent.

Patented Apr. 11, 1916.

Application filed May 23, 1914. Serial No. 840,526.

To all whom it may concern:

Be it known that I, ESTELLA S. ORR, a citizen of the United States, residing at Cleveland, in the county of Cuyahoga and State 5 of Ohio, have invented certain new and useful Improvements in Bust-Forms, of which the following is a specification.

This invention relates to devices adapted to be worn by ladies to maintain the bust in 10 proper position and to accentuate the natural lines of the figure.

It is the object of the invention to provide a device of this kind which can be readily adjusted to the form and which is cool and 15 comfortable. This object is attained by means of a novel combination and arrangement of parts to be hereinafter described and claimed, reference being had to the accompanying drawing, in which—

20 Figure 1 is a plan view of the device before it is adjusted ready for use, and Fig. 2 is a perspective view showing the device adjusted ready for wear.

Referring specifically to the drawing, 5 denotes a sheet of suitable textile fabric having a length greater than twice its width and composed of two layers which are sewed together with a border of lace. The ends of the sheet are rounded. At the edge of 25 the sheet is a pocket 7 to receive draw strings 8, said pocket being formed by two parallel rows of stitchings. The pocket opens to one side of the sheet, midway between its ends, at the top and bottom, at 30 which points the draw strings project so that they may be tied. The sheet also has two spaced, longitudinal pockets 9 for draw strings 10, and a transverse pocket 11 for a draw string 12, said pocket 11 being midway 35 between the ends of the sheet and extending between the top and bottom portions of the pocket 7 and crossing the pockets 9. The pockets 9 open at the middle of the sheet at 40 which points the draw strings 10 project, and the pocket 11 opens at each end where it joins the pocket 7, at which ends the draw string 12 projects. The openings of the 45 pockets 7 and 9 are on one side of the sheet, and the opening of the pocket 11 on the

other side; or the openings may be all on 50 one side of the sheet. If the article is made of silk, the strings may be made of ribbon which would add to its attractiveness if tied on the outside, while in the cheaper grades they would be of tape and might tie on the 55 inner side. Upon drawing the strings 8, 10 and 12, the sheet 5 assumes the outline shown in Fig. 2, and it is held in this shape by tying the ends of the strings. The string 12, when it is drawn, gathers the sheet 60 in the middle so that it assumes the shape of two substantially circular sections, which sections are given a concavo-convex form by drawing the other strings. Thus, the sheet 65 can be readily adjusted to conform to and accentuate the natural lines of the figure. Upon untying and loosening the draw strings, the sheet can be straightened out flat, as shown in Fig. 1, so that it may be 70 easily washed.

By the herein described construction the device permits perfect freedom of movement, and as it has no stiffening devices, it is cool and comfortable. It may be made of 75 cotton, silk or other textile fabric. The device will be fastened to the undergarment by safety pins or other suitable fasteners and it extends well under the arms.

From the foregoing description, it will be seen that simple and efficient means are 80 herein provided for accomplishing the objects of the invention, but while the elements shown and described are well adapted to serve the purpose for which they are intended, it is to be understood that the invention 85 is not limited to the precise construction set forth, but includes within its purview such changes as may be made within the scope of the invention as claimed hereinafter.

I claim:

A bust form comprising a unitary elongated sheet of flexible material having a length greater than twice its breadth whereby to cover the entire bust of the wearer, a 95 draw-string pocket extending across the sheet intermediate its ends and open at both ends, a pair of draw-string pockets extend-

ing around the periphery of the sheet at each end thereof, the ends of the pair of pockets opening opposite each other adjacent to the ends of the first pocket, a plurality of pairs of draw-string pockets extending longitudinally of the sheet and spaced transversely thereof, the pockets of each pair having opposed openings, and draw-

strings in said pockets and arranged for connection of their opposed ends. 10

In testimony whereof I affix my signature in presence of two witnesses.

ESTELLA S. ORR.
